UNITED STATES PATENT OFFICE.

WALTER E. BANNING, OF SYRACUSE, NEW YORK.

SIGN.

SPECIFICATION forming part of Letters Patent No. 293,702, dated February 19, 1884.

Application filed October 11, 1883. (No model.)

To all whom it may concern:

Be it known that I, WALTER E. BANNING, of Syracuse, in the county of Onondaga and State of New York, have invented new and useful 5 Improvements in Street-Lamp Signs, of which the following, taken in connection with the accompanying drawings, is a full, clear, and exact description.

This invention relates to street-signs formed 10 of perforated or stencil plates, the openings of which represent the name of the street. Said signs, when secured in front of the street-lamp, serve to show the name of the street in a very conspicuous and distinct manner in the 15 day-time as well as at night, when the lamp is lighted.

The invention consists, chiefly, in the manner and means of securing the said sign in position in front of the lamp, as hereinafter more fully 20 described, and specifically set forth in the claims.

In the annexed drawings, Figure I shows a street-lamp provided with my improvement. Figs. II and III are enlarged detached views of 25 the street-signs, and Fig. IV illustrates their attachment to the lamp-supporting frame or guards of the lamp.

Similar letters of reference indicate corresponding parts.

30 A and A' represent two street-signs designed to be attached to different sides of a street-lamp, said signs consisting of sheet-metal plates having the name of the street formed by stencil excisions or perforations of the 35 plate. These plates A and A' are formed on one of their ends with two extensions or strips, a a, and on the opposite end with a single strip, b, which latter is near the top of one plate and near the bottom of the other plate, 40 so that said ends of the plates may be placed adjacent and in line with each other when attached to the lamp-frame or its support.

The attachment is effected as follows: The plates A A' are made to reach from one of the 45 guards or lamp-supports c c to another. The ends of the plates having the single strip b are

placed in line with each other, against one of the guards c, and the strip b, which is near the top edge of one of the plates, is wound spirally upward on the guard, while the strip of the 50 other plate is wound spirally downward on said guard, the opposite ends of the plates being placed against the two guards c c, at opposite sides of the first-mentioned guard, and secured in position by winding one of the strips 55 a spirally upward and the other spirally downward on the guard. This spiral attachment in opposite directions on the guard, while simple and convenient, at the same time affords a firm and bracing hold, which effectually prevents the signs from shifting out of line, and also obviates the necessity of perforating the 60 guard for the reception of bolts or rivets, by which to attach the signs, and admits of their ready removal from the lamp or its frame, 65 when desired.

Having described my invention, what I claim is—

1. In combination with a street-lamp and its frame, a stencil sign-plate having extended 70 from its end two strips wound spirally around the guards of the lamp, the one upward and the other downward from the strip, substantially as described and shown.
2. In combination with a street-lamp and 75 its frame, two stencil sign-plates arranged in line with each other, and provided at their adjacent ends, respectively, with a strip disposed in a different plane and wound around the lamp-guard in a different direction from the 80 strip of the adjacent plate, substantially as described and shown.

In testimony whereof I have hereunto signed my name and affixed my seal, in the presence of two attesting witnesses, at Syracuse, in the 85 county of Onondaga, in the State of New York, this 6th day of October, 1883.

WALTER E. BANNING. [L. S.]
